Carpets

No. 5, 6 & 5-

Mar. 12. 1872.

UNITED STATES PATENT OFFICE.

ARTHUR M. KING, OF KIDDERMINSTER, ENGLAND, ASSIGNOR TO HENRY JECKS DIXON & SONS, OF SAME PLACE.

DESIGN FOR A CARPET-PATTERN.

Specification forming part of Design No. 5,645, dated March 12, 1872.

To all whom it may concern:

Be it known that I, ARTHUR MAZEPPA KING, of Kidderminster, county of Worcester, England, have invented a new and original Design for Carpets; and I do hereby declare that the following is a full, clear, and exact description thereof, which will enable others skilled in the art to make and use the same, reference being had to the accompanying photographic illustration, forming part of the specification.

This invention relates to a new design of the main center figure A of a carpet, the same being of the peculiar outline and ornamented in the middle, as shown, and also embraced by an ornamental border, a, of bold and rich design. The invention also consists in the new design of a cross-shaped figure, B, substantially as shown; and finally, too, in a new design of the ornamental scroll C, which forms the ground-work of the carpet.

I claim as my invention—

1. The design of the figure A, as shown.
2. The design of the figure B, as shown.
3. The design of the scroll-work C, as shown.
4. The design for a carpet containing the figures A B and scroll-work C, as shown.

ARTHUR MAZEPPA KING.
